UNITED STATES PATENT OFFICE.

CHARLES C. WIENTGE, OF PROVIDENCE, RHODE ISLAND, ASSIGNOR TO
THE HOWARD STERLING COMPANY, OF SAME PLACE.

DESIGN FOR A RACK.

SPECIFICATION forming part of Design No. 23,333, dated June 5, 1894.

Application filed May 10, 1894. Serial No. 510,800. Term of patent 3½ years.

To all whom it may concern:

Be it known that I, CHARLES C. WIENTGE, of Providence, in the county of Providence and State of Rhode Island, have invented and produced a new and original Design for Racks, of which the following is a specification, reference being had to the accompanying drawings, forming part thereof.

Figure 1 represents a front view of the rack illustrating my new design. Fig. 2 represents an end view thereof.

The general features of my new design for racks consist: first, in the back plate, the peculiar outline of which from the straight lower edge extends upward at the sides in nearly vertical directions, curving irregularly inward and outward to the corner ornaments, then extending inward in irregular curves and projections to meet the central ornament, together with surface ornamentation consisting of a border formed by a succession of foliated scrolls and beadings having leaf-like ornaments at the upper corners and meeting in a central ornament at the top center of the plate, this border surrounding a central plain panel; second, the middle plate or frame supported on scrolled side-supports and consisting of an upper and a lower cross-bar formed by open, scrolled and foliated ornaments, the lower cross-bar being further identified by shell-like extensions from the scrolls and both being joined at the ends by a series of foliated scrolls which extend to the side supports, some of these scrolls having shell-like ornamentation introduced; third, the front plate consisting of the scrolled feet extending upward to form the sides of this plate joined by an upper and a lower cross-bar each formed of a series of foliated scrolls, the upper being further accentuated by the boldness of its scrolls and by the shell-like ornamentation introduced into the side scrolls, the center of the plate being formed by a grid ornament inclosed in scroll work.

In the drawings reference numerals 5 to 13 designate the outline and ornamentation of the back.

Numbers 14 to 21 inclusive designate those of the middle plate or frame, and 22 to 27 inclusive those of the front plate.

Numerals 5 indicates the back plate the plain portion 6 of which is visible through the open-work of the middle and front plates, the outline of this back plate, straight on the lower edge, is defined at the sides by a succession of scrolled beads 7—7 somewhat foliated and raised from the plain surface 6 extending practically vertically to the inwardly curving corner ornament 8—8 from which the leaf-like ornaments 9—9 extend outwardly some of the leaves thereof extending inwardly overlying a portion of the plain surface 6, the inwardly-turned scrolls of the ornaments 8—8 being connected, by the scrolled ornaments 10—10 and 11, with the large central ornament 12 having the grid 13 formed of curving bars, the outline of the back-plate following the outer lines of these curves and scrolls.

Numbers 14—14 designate the scrolled side supports of the middle frame, mounted on these supports are the scrolled leaf-ornaments 15—15 having inwardly turned sprays 16—16 at their upper portions,—from the lower portions of these ornaments 15—15 extend inward the shell-like scrolls 17—17 connecting with the upwardly and inwardly extending scrolls 18—18 foliated and treated with shell-like central portions, these in turn connecting with the lower cross-bar formed of a series of shell-like scrolls 19; on the ornaments 15—15 and 18—18 is the upper cross-bar formed by the series of scrolled ornaments 20—20 joined by the central ornament 21 and having a slight upward inclination.

The feet of the front plate are formed by the scrolled ornaments 22—22 curving inward and upward, from the lower portions of these ornaments extend the scrolls 23—23 with leaf-like ornamentation which connect with the lower portion of the central ornament 24 having a grid-like center 25, and from the upper portions of the ornaments extend the large foliated scrolls 26—26 treated with shell-like ornamentation on their lower edges and connecting with the scrolls 27—27 forming an open-work cross-bar, the scrolls 27—27 of which connect with the central ornament 24.

The back-plate 5 and the front and middle frames are mounted on the bottom-plate 28,

the scrolled ornaments 22—22 of the front frame extending below the same, the back 5 and the middle frame being connected by the S-shaped ornament 29, while the middle 5 frame or plate is connected with the front by a similar ornament 30.

What I claim is—

1. In a design for racks, the back plate as herein shown and described.
- 10 2. In a design for racks, the middle plate as herein shown and described.

3. In a design for racks, the front heroin shown and described.

1. The design for racks as herein shown and described.

In witness whereof I have hereunto set my hand.

CHARLES C. WIENTGE.

Witnesses:

HENRY J. MILLER,
M. F. BLIGH.
